UNITED STATES PATENT OFFICE.

HARRY COOKE, JR., OF GARFIELD, NEW JERSEY.

TRAFFIC SIGNAL.

Application filed April 1, 1926. Serial No. 99,124.

This invention relates to traffic signals, and has especial reference to the type of traffic signals which are placed in roadways and serve for guiding traffic.

One of the principal objects of the present invention is to provide in a traffic signal a pensile lamp casing which is cushioned so that electrical connections and divers other parts will not be broken away when the signal is subjected to blows or shocks from passing vehicles.

Another object of the invention is to provide a traffic signal stand characterized by means which will cause a flood of light to be directed to the roadway.

With the foregoing and other objects in view, the invention resides in the particular construction and arrangement of parts hereinafter described and illustrated in the accompanying drawings.

The nature of the invention and its distinguishing features and advantages will appear when the following specification is read and connected with the accompanying drawings, in which—

Figure 1 is a side elevation, partly in section, of a traffic signal embodying the present invention;

Figure 2 is a plan view, partly in section, of the top of the signal;

Figure 3 is a horizontal sectional view taken on the line 3—3 of Figure 1;

Figure 4 is a sectional view illustrating the lamp casing suspension means.

The illustrated embodiment of the present invention, generally stated, comprises a supporting structure 10, a lamp casing 11, means 12 for loosely suspending the lamp casing 11 from the structure 10, and means 14 which cushions the lamp casing 11 to restrain the swaying movement which the lamp casing is permitted to have.

The supporting structure 10 in the present instance includes a foundation block 15, preferably of cement, which is adapted to be anchored to the roadway in any preferred manner.

Arranged on the block 15 is a base 16, and the said base is secured to the block 15 by suitable anchoring bolts 17. The base 16 is provided with sockets 18, there being one arranged at each corner of the base 16. In the present instance, the base 16 is hollow, as at 19. Uprights 20 are provided. The uprights are equal in number to the number of sockets 18 with which they are respec-

tively connected, as at 21. Each upright 20 is of tubular construction and its upper end is curved and attached, as at 22, to a socket 23 of a suspension member 24. A cap 25, of any preferred design, is secured in place on the member 24.

The means 12 for loosely suspending the lamp casing 11 includes the suspension member 24, and also includes the suspension member 26 which is arranged in a recess 27 in the member 24, and a suspension member 28 secured, as at 29, to the top of the lamp casing 11.

The member 26 is provided with a cavity 30 which conforms to and accommodates the semi-spherical part 31 of the member 28 to allow the lamp casing to sway. The cap 25 is provided with a recess 32; the member 26 is provided with an opening 33 which is extended into the cavity 30, and the member 24 has an opening 34, all of which permit the suspension member 28 to have the desired movement.

It is to be noted that the member 28 is of hollow construction so as to permit lead in wires to be led into the lamp casing 11. In this connection, it is also to be noted that one of the uprights 20 serves as a conduit which is in communication with a conduit 35 through and by virtue of the recess 19 in the base 16 and the passage 36 between the recess 19 and the lower end of the upright. The member 24 is provided with an opening 37, and the member 26 and part 31 are cut away, as at 38 and 39 respectively, to properly accommodate the conduit through which the lead in wires extend.

The lamp casing 11 may be of any preferred construction, is hollow, and is provided with visors for directing the rays of light from the lamps which will be arranged in the casing.

The means 14 for yieldably placing the lamp casing under constraint, in the present instance, comprises fastening connections 40 and 41 arranged respectively on the uprights 20 and the bottom of the lamp casing 11. Springs 42 are arranged between the fastening connections 40 and 41. It will now be apparent that the lamp casing will be allowed to have movement, which will be a swaying movement, and that this movement will be limited by the springs 42 which serve as cushions. By permitting the lamp casing to have a certain amount of movement, breaking of electrical connections and other divers parts is obviated, and the springs serve to

5 maintain the lamp casing centrally located between the uprights 20. In accordance with another feature of the present invention and due to the fact that the lamp casing is suspended, it is possible to employ a lamp 43 on the base 16 and a reflector 44 above the lamp to reflect the rays of light emitted from the lamp 43 downwardly on the roadway.

10 A reflector 44 may be embodied in the bottom of the lamp casing 11 or may form a separate part and be attached to the bottom of the lamp casing. It will, therefore, be apparent that adequate means is provided for causing a flood of light to be directed to the 15 roadway so that the operators of vehicles will avoid collision with the lower parts of the signal.

Having thus described my invention, I claim:

20 1. In a traffic signal, a base, uprights on the base, an upper suspension member supported by said uprights, a lamp casing, a substantially semi-spherical member on the top of said lamp casing which is received in 25 a recess in said upper suspension member, connecting members on the uprights respectively and on the bottom of the lamp casing, and springs arranged respectively between the connecting members on the uprights and the bottom of the lamp casing.

30 2. In a traffic signal, a base, uprights on the base, a lamp casing, means between the uprights and the lamp casing suspending the lamp casing to permit the lamp casing to sway, said means comprising a suspension member which is connected to the uprights, 35 a second suspension member arranged within and supported by the first mentioned suspension member, and a third suspension member connected to the top of the lamp casing, said third suspension member directly supported by and movable with respect to the second suspension member, said suspension members in correlation adapted to accommodate the conduit for the lead wires of the electric lamps within said lamp casing.

40 member connected to the top of the lamp casing, said third suspension member directly supported by and universally movable with respect to the second suspension member.

45 3. In a traffic signal, a base, uprights on the base, a lamp casing, means between the uprights and the lamp casing suspending the lamp casing to permit the lamp casing to sway, said means comprising a suspension member which is connected to the uprights, 50 a second suspension member arranged within and supported by the first mentioned suspension member, a third suspension member connected to the top of the lamp casing, said third suspension member directly supported by and universally movable with respect to the second suspension member, and cushioning means between the lamp casing and the 55 uprights.

60 4. In a traffic signal, a base, uprights on the base, an electric lamp casing, means between the uprights and the lamp casing suspending the lamp casing to permit the lamp casing to sway, said means comprising a suspension member which is connected to the uprights, 65 a second suspension member arranged within and supported by the first mentioned suspension member, and a third suspension member connected to the top of the lamp casing, said third suspension member directly supported by and movable with respect to the second suspension member, said suspension members in correlation adapted to 70 accommodate the conduit for the lead wires of the electric lamps within said lamp casing.

HARRY COOKE, JR.
